UNITED STATES PATENT OFFICE

GEORGE M. DOERSCH, OF ANTIGO, WISCONSIN.

BUNG-EXTRACTOR.

SPECIFICATION forming part of Letters Patent No. 293,232, dated February 12, 1884.

Application filed December 26, 1883. (No model.)

To all whom it may concern:

Be it known that I, GEORGE M. DOERSCH, a citizen of the United States, residing at Antigo, in the county of Langlade and State of Wisconsin, have invented certain new and useful Improvements in Bung-Extractors; and I do hereby declare the following to be a full, clear, and exact description of the invention, such as will enable others skilled in the art to 5
10 which it appertains to make and use the same, reference being had to the accompanying drawing, and to letters or figures of reference marked thereon, which form a part of this specification.

15 My invention relates to improvements in that class of bung-extractors in which a knife-shaped point having a blunt or non-cutting back and a shank from its back, on which shank, at a distance from the knife, is a handle-supporting shoulder, and the knife being driven 20 through the bung and turned either to the right or the left, so that the knife cannot return through the opening it has made, the bung is drawn out by a claw-iron or other suitable 25 instrument applied as a lever to the shank at and beneath the shoulder; and the object of my invention is to provide a rigid collar on the shank of the bung-extractor, interposed 30 between the back of the knife and the shoulder and at a distance from either, whereby in driving the knife into the bung the extractor will not go in up to the shoulder, as otherwise it frequently does, rendering it inconvenient to apply the claw-iron, but will be stopped by 35 the rigid collar, thereby providing a convenient space for the ready application of the claw-iron for withdrawing the bung.

In the drawing, which is a perspective view 40 of the improved bung-extractor, A represents the knife, having its lower edge or edges sharp and its back square and blunt. B is the shank, affixed to the knife A at its back. C is the handle-supporting shoulder, beneath and against which the claw-iron is applied to draw 45 out the bung, and D is the collar, rigidly attached to the shank B at such distance from

the knife A as to allow the knife to be driven entirely through the bung, and of such size and shape as, when the extractor is being driven into the bung, to strike against the 50 bung and arrest its further progress, said collar being also at such distance from the shoulder C as to permit the application of the claw-iron to the shank between the shoulder and the collar.

55 Heretofore bung-extractors of the character of those to which my improvement relates have had no collar, and in use were likely to be driven down to and against the handle-supporting shoulder, thereby rendering it inconvenient to apply the claw-iron, except by first 60 pulling back the extractor sufficiently for that purpose; but with my collar the extractor cannot be driven in up to the shoulder, but will always be arrested by the collar, leaving the 65 space clear on the shank between the collar and the shoulder, to which the claw-iron can be applied without the delay incident to partially withdrawing the extractor for that purpose.

70 Having thus described my invention, what I claim as new, and desire to secure by Letters Patent, is—

1. The combination, with the shank of a bung-extractor, of a collar interposed between 75 the blade and the handle-supporting shoulder, adapted to arrest the downward movement of the instrument, whereby a claw-iron may be readily interposed between said collar and the shoulder of the extractor in extracting the 80 bung, substantially as and for the purpose specified.

2. In bung-extractors, the rigid collar D, in combination with the knife A, the shank B, and the shoulder C, substantially as and for 85 the purpose specified.

In testimony whereof I affix my signature in presence of two witnesses.

GEO. M. DOERSCH.
